UNITED STATES PATENT OFFICE.

JOHN COSTELLO, OF ATTLEBOROUGH, MASS., ASSIGNOR OF ONE-HALF TO
CLARENCE L. WATSON AND FRED A. NEWELL, BOTH OF SAME PLACE.

CUFF-BUTTON.

SPECIFICATION forming part of Letters Patent No. 350,915, dated October 19, 1886.

Application filed July 6, 1886. Serial No. 207,232. (No model.)

To all whom it may concern:

Be it known that I, JOHN COSTELLO, of Attleborough, in the county of Bristol and State of Massachusetts, have invented certain new and useful Improvements in Detachable Buttons; and I do hereby declare the following to be a full, clear, and exact description of the invention, such as will enable others skilled in the art to which it appertains to make and use the same.

My invention relates to an improvement in detachable buttons, and more particularly in detachable buttons for cuffs, collars, sleeves, and the like.

The object is to provide a device which may be conveniently manipulated and firmly secured against displacement, and one which may be manufactured at a small initial cost.

With these ends in view my invention consists in certain features of construction and combinations of parts, as will be hereinafter fully described, and pointed out in the claims.

In the accompanying drawings, Figure 1 is a vertical longitudinal section with one arm or hook-shaped member in its locked position and the other in its unlocked position. Fig. 2 is a plan view of the back plate with its arms removed. Fig. 3 is a detached view of one of the arms. Fig. 4 is a longitudinal vertical section of a modification with one hook-shaped member or arm elevated and the other depressed. Fig. 5 is a plan view of the back plate. Fig. 6 is a detached view of one of the arms. Fig. 7 is a vertical longitudinal section of a second modified form. Fig. 8 is a plan view with the arms removed, and Fig. 9 is a detached view of one of the arms.

A represents an ordinary back plate, on which the ornamental head is mounted in the usual manner. The back plate may be of any form or material, and is provided with a pair of narrow elongated slots, B, located side by side, and conveniently separated by a narrow partition, C, formed integral with the back plate, and preferably slightly countersunk. The partition C is provided at its opposite ends with outwardly-projecting arms a^2 , which extend across the extreme ends of the slots B. The bars or pintles b, which transversely span the slots B, are preferably made integral

with the back plate A and the partition C, and are each located at one side of the longitudinal center of the slot. A pair of spring-plates, D, (or only one may be used, if found sufficient,) are located over the slots, and are firmly secured in place between the plates of the cap. Between the springs and the bars or pintles b the cams of the hook-shaped members or arms E are secured. The arms E are preferably broadened and slightly curved at their free ends and terminate in a cam, d, at the hinged end. This cam consists of the portion e, forming the flat face e' , about one-half the length of the free portion of the arm and approximately at right angles thereto. It is also provided with a second rectangular turn at point e^2 , forming a re-entering angle, e^3 ; thence it terminates in a goose-necked shoulder, e^4 . Thus the cam is provided with two straight faces, one of which is always in frictional contact or engagement with a spring-plate, D. When the arms are together or in extreme elevated adjustment, the face e' is in engagement with the spring-plate, in which position it is firmly held by the tension of the said spring-plate. When the arms are separated or in their locked adjustment, the face e^4 between angle e^3 and shoulder e^4 is in engagement with the spring-plate, and the nose e^4 furnishes a stop for rigidly holding the arms at a convenient distance from the face-plate.

In the modification shown in Figs. 4, 5, and 6 the back plate, A, is conveniently set in a rim, F, and the entire surface of the back plate and partition between the two slots are in the same plane. The difference between this construction and the one described, however, is in the termination of the cam end of the arm. In this case, instead of terminating in a goose-necked shoulder and nose, the end e^4 is turned slightly backward and approximately parallel to the face e' of the arm. Thus it will readily be seen that although the arms are normally depressed by the frictional contact of the cam against the spring-plate D, yet they are allowed to yield to a slight extent, and may be depressed until their free ends impinge against the back plate, because of the absence of the nose e^4 . This slight yielding movement is often found desirable, especially when the

button is suddenly forced against the body, when by the slight yielding motion a bruise of the skin is often prevented.

In the modification shown in Figs. 7, 8, and 9 the face e' is slightly elongated; but the principal difference between this form and the two already described is that a common pintle, b , located in the middle of the back plate pivotally secures both arms E . By this construction the arms open wider than the other two described.

It is evident that other slight changes might be resorted to in the form and arrangement of the several parts described without departing from the spirit and scope of my invention; hence I do not wish to limit myself to the particular construction herein set forth; but,

Having fully described my invention, what I claim as new, and desire to secure by Letters Patent, is—

1. In a detachable button, the combination, with a slotted back plate, the spring connected therewith, and the bars or pintles, of the arms loosely mounted on said bars or pintles,

and provided with hooked ends, each latter having a stop adapted to engage the back plate, for limiting the movement of the arm in one direction, and two elongated flat faces which are engaged by the spring to retain the arm in a locked or unlocked position, substantially as set forth.

2. In a detachable button, the combination, with the back plate having parallel slots separated by a thin partition, the spring connected to the back plate, and the bars or pintles located on opposite sides of the longitudinal center of the back plate, with their inner ends resting on or integral with the partition separating the slots and spanning their respective slots, of the arms provided with hooked ends, substantially as set forth.

In testimony whereof I have signed this specification in the presence of two subscribing witnesses.

JOHN COSTELLO.
